UNITED STATES PATENT OFFICE.

VINCENT BENDIX, OF CHICAGO, ILLINOIS.

ENGINE-STARTER.

1,372,264.

Specification of Letters Patent. Patented Mar. 22, 1921.

Application filed February 7, 1920. Serial No. 357,072.

To all whom it may concern:

Be it known that I, VINCENT BENDIX, a citizen of the United States, residing at Chicago, in the county of Cook and State of Illinois, have invented certain new and useful Improvements in Engine-Starters, of which the following is a specification.

My invention relates to an engine starter such as used for the starting of internal combustion engines and pertains to the drive or transmission thereof. The object of my invention is to produce a simple and novel construction of drive whose advantageous features of construction and mode of operation will be apparent from the description hereinafter given. Speaking in general terms my drive comprises a rotatable member or screw shaft of novel formation and provided with a driving member mounted thereon and adapted to engage either directly or indirectly with the engine member such as the flywheel of the engine.

In the drawing Figure 1 is a sectional elevation of a starter system illustrating a drive embodying my invention and Fig. 2 a section on the line 2-2 of Fig. 1 but on a larger scale.

My drive or transmission belongs to that class known as the Eclipse-Bendix drive and my invention has been embodied in a construction containing certain features or specific construction of that drive, but it will be understood that my invention is not limited to any such specific construction unless so required by the claims. It will also be understood that while I have shown my invention embodied in a starter system of the single reduction type it is equally applicable to the double reduction type, and also that it is equally applicable to the inboard type as well as to the outboard type herein shown.

Referring to the particular embodiment of my invention as herein illustrated, the prime mover is here a starting motor indicated at 1 and the same is provided with an extended armature shaft 2 upon which the drive is mounted and to which it is operatively connected. A collar 3 forming a driving head is secured to the inner end of the shaft 2 and is operatively connected to the driven head 4 of the screw shaft which is here in the form of a sleeve mounted on the outer end of the shaft 2. The driving and driven heads are connected by a yielding driving connection such as the coiled spring 5 whose

ends are anchored to said heads respectively by means of the studs 6 and 7.

The screw shaft or sleeve is provided with a screw threaded portion 8 which is here shown at its outer end and another portion 9 which is plain except for the provision of the spiral groove 10 and the circumferential groove 11. The spiral groove is made at a predetermined angle or pitch according to the desired speed of the longitudinal movement of the pinion as hereinafter described. The screw shaft is provided at its outer end with the usual stop nut 12.

The driving member which is here in shown the form of a pinion 13 is adapted to drive an engine member either directly or indirectly but in the present instance this pinion is adapted to constitute the only driving member upon the drive itself and is also adapted to directly engage the engine member such as the flywheel 14. This pinion has a central screw threaded bore and is adapted to screw upon the screw threads 8 of the sleeve. This pinion is provided at its inner end with an extension or apron 15 through which passes through a radial hole a yielding plunger 16 whose rounded inner end is held projected in the circumferential groove 11 on the screw shaft or sleeve. According to the detailed construction herein shown this plunger is provided intermediate its length with an enlargement or collar 17 and with an outwardly extending stem 18. This plunger is yieldingly pressed inwardly by a spring pressure by means of the spring ring 19 having an opening at its central portion through which the pin 18 passes and adapted to yieldingly clamp itself upon the apron 15, in a manner clearly indicated in Fig. 2. This spring therefore bears inwardly upon the collar 19 and thereby presses the plunger into yielding engagement with the groove 11.

The spiral groove 10 runs into the groove 11 and such groove 10 at its juncture with the groove 11 is made somewhat deeper as indicated at 20 with the result that when the screw shaft is rotated by the motor and such deeper portion is presented to the plunger, there will be a tendency of the plunger to leave the groove 11 and follow the groove 10 with the result that owing to the rotation of the screw shaft and the engagement of the plunger 16 with the groove 10 the pinion will be advanced longitudinally of the screw shaft and the screw threads of the pinion 110

will be brought into screw threaded connection with the screw threads 8 and will be screwed thereupon. When the pinion is arrested in its longitudinal movement by the 5 stop nut it will partake of the rotary movement of the screw shaft and as it is at this time in mesh with the flywheel, the engine will be rotated and started. When the engine starts on its own power the pinion will 10 be automatically demeshed in the well-known manner and the pinion will be restored to its normal position shown in Fig. 1 at which time the plunger 16 will take its position in the groove 11. The pinion is not 15 only directed in its longitudinal movement by this plunger but is held in its normal position against any drifting due to vibration or other causes.

In the event that the pinion teeth and flywheel teeth should abut end to end instead of obtaining register thereof, the construction is such that while the shaft will continue to rotate the pinion will be stopped in its longitudinal movement and the plunger 25 will jump out of the groove 10 which is rather shallow and when another portion of the groove is presented thereto in the continued rotation of the shaft, the plunger will drop therein and will be again presented to the flywheel teeth. This action 30 will continue until proper register and meshing of the teeth is obtained.

I claim:

1. An engine starter drive including a rotatable shaft, a driving member having a screw threaded bore and mounted thereon for longitudinal movement thereof and rotary movement therewith, said shaft having a screw threaded portion on which such member is threaded when in driving position, and having a non-screw-threaded portion on which such member rests when in normal position, and automatic means independent of the screw threaded bore of 45 such member and coöperating with such non-screw-threaded portion for moving the member longitudinally into screw threaded engagement with the screw-threaded portion of the shaft.
2. An engine starter drive including a rotatable shaft, a driving member having a screw threaded bore and mounted thereon for longitudinal movement thereof and rotary movement therewith, said shaft having a screw threaded portion on which such member is threaded when in driving position, and automatic means independent of the screw threaded bore of such member for moving the member longitudinally into 55 screw threaded engagement with the screw-threaded portion of the shaft.
3. An engine starter drive including a rotatable shaft, a driving member having a screw threaded bore and mounted thereon for longitudinal movement thereof and 65

tary movement therewith, said shaft having a screw threaded portion on which such member is threaded when in driving position, and having a non-screw threaded portion on which such member rests when in 70 normal position and which is provided with a spiral groove, said driving member having a projection coöperating with the groove whereby the member is automatically advanced longitudinally into screw threaded 75 engagement with the shaft when the latter is rotated.

4. An engine starter drive including a rotatable shaft, a driving member having a screw threaded bore and mounted thereon 80 for longitudinal movement thereof and rotary movement therewith, said shaft having a screw threaded portion on which such member is threaded when in driving position, and having a non-screw threaded portion on which such member rests when in 85 normal position and which is provided with a spiral groove, and a yielding plunger mounted on the member and coöperating with the groove whereby the member is automatically advanced longitudinally into screw threaded engagement with the shaft when the latter is rotated.

5. An engine starter drive including a rotatable shaft, a driving member having a screw threaded bore and mounted thereon for longitudinal movement thereof and rotary movement therewith, said shaft having a screw threaded portion on which such member is threaded when in driving position, and having a non-screw threaded portion on which such member rests when in 90 normal position and which is provided with a spiral groove, and a spring-pressed plunger mounted on said member and held projected into such groove whereby the member is automatically advanced longitudinally into screw threaded engagement with the shaft when the latter is rotated.

6. An engine starter drive including a rotatable shaft, a driving member having a screw threaded bore and mounted thereon for longitudinal movement thereof and rotary movement therewith, said shaft having a screw threaded portion on which such member is threaded when in driving position, and having a non-screw threaded portion on which such member rests when in 110 normal position and which is provided with a spiral groove and a circumferential groove 115 communicating with one end thereof, and means carried by said member and coöperating with the grooves for retaining such member in normal position and for insuring its longitudinal movement.

7. An engine starter drive including a rotatable shaft, a driving member having a screw threaded bore and mounted thereon for longitudinal movement thereof and rotary movement therewith, said shaft having 120

125

130

a screw threaded portion on which such member is threaded when in driving position, and having a non-screw threaded portion on which such member rests when in 5 normal position and which is provided with a spiral groove and a circumferential groove communicating with one end thereof, and means carried by said member and coöperating with the grooves comprising a pin carried 10 by said member and yieldingly held projected into the circumferential groove when the member is in normal position and into the spiral groove when the shaft is rotated and the member is advancing longitudinally.

8. An engine starter drive including a rotatable shaft, a driving member having a screw threaded bore and mounted thereon for longitudinal movement thereof and rotary movement therewith, said shaft having 20 a screw threaded portion on which such member is threaded when in driving position, and having a non-screw threaded portion on which such member rests when in normal 25 position and which is provided with a spiral groove and a circumferential groove communicating with one end thereof, and means carried by said member and coöperating with the grooves comprising a pin carried

30 by said member and yieldingly held projected into the circumferential groove when the member is in normal position to hold it in such position and into the spiral groove when the shaft is rotated to insure the movement of such member longitudinally, the 35 communicating end of the spiral groove being deepened to insure the passage of the pin in the groove when the shaft is rotated.

9. An engine starter drive including a rotatable shaft, a driving member having a screw threaded bore and mounted thereon for longitudinal movement thereof and rotary movement therewith, said shaft having 40 a screw threaded portion on which such member is threaded when in driving position and having a non-screw threaded portion on which such member rests when in normal position and which is provided with a spiral groove, a plunger mounted in the member and coöperating with the groove 45 whereby the member is automatically advanced longitudinally into screw threaded engagement with the shaft when the latter is rotated, and a split spring ring partially 50 encompassing the member and bearing 55 against the plunger.

VINCENT BENDIX.
